UNITED STATES PATENT OFFICE

2,375,143

CONCRETE DAM STRUCTURE

Henry Sorensen, Los Angeles, Calif.

Application September 19, 1944, Serial No. 554,735

3 Claims. (Cl. 61—32)

My invention, herein, relates to a specific utilization of my invention for the erection of mass concrete blocks, as contained in my U. S. Patents #1,888,097, Nov. 15, 1932, and #1,889,267 Nov. 29 1932, and resides in providing quick and effective accessibility to every interior part of a concrete dam for the repairs of damages done by bombings, or of damages originating from any other cause, while avoiding the lowering of the stored waters, which are the source from where hydroelectric power is obtained.

I have described my invention in the following specification and illustrated the same in the accompanying drawing, of which:

Fig. 1 is an interior vertical cross section of the dam.

Fig. 2 is a fragmentary vertical section taken at 2—2 of Fig. 1.

Fig. 3 is a fragmentary horizontal section taken at 3—3 of Fig. 1.

Fig. 4 is a fragmentary part of the dam illustrating a removable trap-door with its attachment and which covers the entrance to the dam.

Similar numerals designate similar parts and numeral 1 designates a concrete dam. 2 designates rectangular shaped shafts. 3 designates the one set of opposed shaft walls. 4 designates the other set of opposed shaft walls. 5 designates galleries. 6 designates slanting upper ends of walls 3. 7 designates steel reinforcements. 8 designates drainage tunnels. 9 designates drainage valves. 10 designates a vertical side of dam 1. 11 designates a slanting side of dam 1. 12 designates entrance openings in the crown of dam 1. 13 designates crushed rock. 14 designates stored waters. 15 designates bed-rock foundation. 16 designates a solid end plate covering the toe of dam 1. 17 designates bolts holding end plate 16. 18 designates the floor of dam 1 resting on bed-rock 15. 19 designates a trap-door covering entrance opening 12. 20 designates bolts securing trap-door 19. 21 designates an interior water locking and pressure imposing device. 22 designates cut threads in device 21 and trap-door 19. 23 designates openings through walls 4. 24 designates water occupying the interior of dam 1.

The opposed walls 4, of shafts 2, firmly connect the vertical side 10 with the slanting side 11, sides 10 and 11 being opposed to each other.

The upper parts of the other opposed walls 3, of shafts 2, and which connect walls 4, terminate in slanting ends 6. These slanting ends 6 have, preferably, the same pitch as slanting side 11, said parts 6 and 11 being suitably spaced, thus forming slanting galleries 5 parallel with slanting

side 11, the sides of said galleries 5 being formed by the opposed walls 4 with the roof and floor of said galleries 5 formed, respectively, by slanting side 11 and slanting ends 6, while said walls 4 rigidly connect side 10 with side 11, of dam 1, as above referred to.

On Fig. 2, which is a vertical cross section taken at 2—2 on Fig. 1, I have illustrated the four surrounding surfaces of slanting galleries 5, viz:—

10 their two sides formed by walls 4 with their floors formed by slanting tops 6, of walls 3, and their roofs formed by the slanting side 11.

15 I fill shafts 2 with a removable material, preferably crushed rock 13, flush with slanting floors 6 of galleries 5 and, as will be understood by Fig. 1, the upper parts of shafts 2 then become furnished with continuous slanting galleries 5 having, preferably, a parallel pitch with slanting side 11.

20 Each one of the parallel and rectilineal slanting rows of galleries 5, which follow the pitch of slanting side 11, is reached through their openings 12 in the crown of dam 1, with each individual one of shafts 2 accessible for repair work by

25 sinking in rock 13 from galleries 5, while the interior of side 11 is equally well reached from any overhead place of galleries 5. Openings 12 are covered by removable trap-doors 19, which are firmly held by bolts 20, when closed.

30 Should side 10, of dam 1, become damaged by bombings, or damaged by any other cause, then all that need be done is first to open drainage valves 9, valves 9 being securely held by end-plate 16 which, in turn, is firmly held by bolts 17, whereupon stop-gap appliances can be lowered against the outside of side 10 to cover the damaged part.

The pressure from stored waters 14 will then facilitate a tight contact between said appliances and the face of side 10, while all spillwaters be-

40 come drained through the crushed rock 13 and tunnels 8 in the bottom of walls 3, and repair crews, when sinking in shafts 2 and after first having removed trap-doors 19, will have a firm footing on crushed rock 13, from where they will

45 easily and conveniently make any repairs from the interior of dam 1,—no lowering of the stored waters 14, as little as any laborious coffer-dams, being required to facilitate the repair work, due to the fact, as stated, that all repair work is then conducted from the interior of dam 1.

Dam 1 comprises one block of concrete, between its upstream side 10 and its downstream side 11, with its interior honeycombed by its galleries 5, its shafts 2 and its drainage tunnels 8.

50 Downstream side 11 consists of an unbroken

and integral sheet of concrete with steel members 7 interlocking with other steel members 7 in walls 4 and floor 18 of shafts 2, as illustrated in Fig. 2, to resist the water-pressure originating in the interior of dam 1 and to which I will make further references below.

Floor 18, of dam 1, rests on bed-rock foundation 15, and I prefer to firmly unite side 10 and side 11 with walls 3 and 4, as well as with floor 18, into one integral mass by means of reinforcements 7, as illustrated on Fig. 1, Fig. 2 and Fig. 3 and this lashing together of said parts 3, 4, 10, 11 and 18 enables me to achieve the following:

When the interior of dam 1 becomes filled with waters, due to a cracking of side 10, then I counter act the pressure of said interior waters, against the inside of side 11, by means of the weight of those same waters because;—the weight of said interior waters, bearing down on floor 18, then holds side 11 to floor 18 through their connecting walls 4;—thus I convert side 11 into a secondary line of defense for the maintenance of stored waters 14 to their full hight,—after the usefulness of side 10, for that purpose, has been temporarily destroyed by bombings and until the damage to side 10 is repaired;—the maintained hight of the stored waters 14 being the pre-requisite for the uninterrupted production of hydroelectric power.

In other words:—down-stream side 11, which I have called the second defense line of dam 1, holds the stored waters 14 to their full hight, till the above referred to stop-gap appliances are in place on the outside of side 10.

It will readily be understood, that alone by the application of my simple and novel invention to use slanting galleries 5, from where to sink into shafts 2 for repair work, can efficient and quick repairs be conducted from the inside of dam 1.

Had I used a system of horizontal tunnels, the one below the other, then the cumbersome method of also having to raise in shafts 2, instead of sinking everywhere, would so hamper and retard all work, as to make the use of horizontal tunnels highly undesirable,—besides which practically all repair work would then have to be conducted from the lower parts of dam 1 and from there upwards.

My simple and novel invention of using slanting galleries 5, supported by drainage tunnels 8, makes my invention a practical reality to maintain the full hight of the stored waters 14 during war-time bombings.

The spillway, which carries away the surplus water, is not illustrated in the drawings, but that water can be diverted by any known and desired method.

Fig. 4 discloses a modification of my invention, which is in line with my invention to safeguard hydro-electric power during war-time emergencies and illustrates an enlarged fragmentary drawing of the upper part of dam 1, having a device 21 which locks and imposes pressure on interior waters 24 of dam 1, said device being attached to trap-door 19.

Waters 24 are filled, throughout the whole interior of dam 1, clear up to water locking and pressure imposing device 21, said device 21 consisting of a cylindrical and threaded body, which is adapted to be turned down in corresponding threads 22 occupying a round hole in trap-door

19 so that, when device 21 is turned down in firm contact with waters 24, said waters 24 then become an inflexible and locked hydro unit, which no known concussion can shatter or heave apart, before the outside walls of dam 1 are cracked open,—but before said cracking of the outside walls of dam 1 can take place, the interior locked and pressure subjected hydro-unit 24 will have served the purpose to act as a powerful protection against any outside bombing shocks by neutralizing, absorbing and distributing said shocks throughout the whole cubic contents of the interior locked and pressure subjected waters 24,—thereby materially lessening the effects of the shocks caused by the bombs, exploded against the outside of dam 1, and in that manner greatly reduce the damage, otherwise caused.

I prefer to cut openings 23 through the top of walls 4, thereby making it necessary to only have one locking and pressure imposing device 21 for the whole block of dam 1, in which waters 24 are filled, these openings 23 making it possible to instantaneously absorb, distribute and neutralize the bombing shocks, against the outside of dam 1, throughout the whole interior mass of the locked and pressure subjected waters 24, under the well known law:—that waters, when filling a closed container, will instantaneously distribute any pressure, at one given point, evenly throughout the whole interior of said container, regardless of the shape of said container.

Various modifications may be made without departing from the spirit of my invention.

I claim:

1. In a concrete dam comprising an integral block between its upstream and downstream sides and containing a row of controlled drainage equipped spaced shafts; providing means whereby said shafts are totally incased internal slanting galleries connecting the upper parts of said incased shafts, an entrance to said galleries passing through the higher portion of said dam and means adapted to counteract interior water-pressures against the inside of said downstream side.

2. In a concrete dam comprising an integral block between its upstream and downstream sides and containing a row of controlled drainage equipped spaced shafts; providing means whereby said shafts are totally incased internal slanting galleries connecting the upper parts of said incased shafts, an entrance to said galleries passing through the crown of said dam, a trap-door controlling said entrance and means adapted to counteract interior water-pressures against the inside of said downstream side.

3. In a concrete dam comprising an integral block between its upstream and downstream sides and containing a row of controlled drainage equipped spaced shafts; providing means whereby said shafts are totally incased internal slanting galleries connecting the upper parts of said incased shafts, an entrance to said galleries passing through the crown of said dam, a trap-door controlling said entrance, said trap-door sealing transient water filling the interior of said dam, a pressure imposing device operating on said water and means adapted to counteract interior water-pressures against the inside of said downstream side.
